UNITED STATES PATENT OFFICE.

GUSTAV RÖMISCH, OF VIENNA, AUSTRIA.

TOBACCO-PIPE.

SPECIFICATION forming part of Letters Patent No. 234,810, dated November 23, 1880.

Application filed September 20, 1880. (No model.) Patented in Austria-Hungary March 11, 1880.

To all whom it may concern:

Be it known that I, GUSTAV RÖMISCH, of Austria, residing at Vienna, in Empire of Austria, have invented certain new and useful Improvements in Tobacco-Pipes; and I do hereby declare that the following is a full, clear, and exact description of the invention, which will enable others skilled in the art to which it appertains to make and use the same.

10 In all pipes, nargilehs, &c., heretofore in use the lower layers of tobacco become saturated by the products of combustion and distillation penetrating them, and a great deal of tobacco is therefore rendered perfectly useless or 15 receives a disagreeable, sharp, and unhealthy taste.

The object of my improvements is to obviate this defect; and to that end the invention consists, first, in a pipe-bowl, the combination 20 of a removable combustion-chamber having a contracted combustion-zone and a tobacco-receptacle arranged to form an annular diving-flue between it and the pipe-bowl and feeding devices to feed the tobacco to said combustion-zone, all as hereinafter set forth; second, in a pipe-bowl, the combination of a removable tobacco-receptacle arranged to form an annular diving-flue between it and said bowl, and provided with a foot or base to form a chamber below said receptacle and between it and the pipe-bowl, a removable combustion-chamber having a contracted combustion-zone, and feeding devices for the tobacco to feed the latter to said zone, all as hereinafter set forth; third, in a 25 pipe-bowl, the combination therewith of a removable combustion-chamber, a removable tobacco-receptacle, and removable feeding devices to feed the tobacco to the combustion-chamber, all as hereinafter fully described; 30 and, lastly, the invention consists in certain minor details of construction and arrangement, all as hereinafter fully described, and as illustrated in the accompanying sheet of drawings, in which—

45 Figure 1 is an elevation, and Fig. 2 a longitudinal section, of pipe-bowl embodying my improvements. Fig. 3 is a longitudinal section thereof, showing the position of parts when filled with tobacco. Figs. 4 and 5 are 50 elevations of the combustion and tobacco cylinders. Fig. 6 is a longitudinal section of the

bowl, showing the bowl with the combustion and tobacco cylinders removed. Figs. 7 and 55 8 are transverse sections on lines *a b* and *c d*, respectively, of Fig. 3. Figs. 9, 10, 11, and 12 show a slight modification in the arrangement of the parts.

In the above drawings like letters of reference are employed to indicate like parts wherever such may occur, and in these figures A represents the bowl of the pipe, which may be made of any suitable material and of any desired shape, exteriorly as well as interiorly, so far as this latter construction may be consistent with the proper function of the 65 parts combined therewith.

I preferably make the interior *a* of the bowl A of cylindrical form, but of unequal diameter, the latter being wider from a point, *a'*, to the top of the bowl, as shown, Figs. 2, 3, and 70 7, for purposes hereinafter explained.

The upper end of the bowl is provided with a threaded metallic sleeve, *a²*, upon which is screwed the combustion-cylinder B, provided with a lid, *b*, a flaring mouth, *b'*, and a lower 75 cylindrical combustion-chamber, *b²*, forming between the two the contracted neck shown at *g*.

The cylinder B is provided with an annular sleeve, *b³*, screw-threaded interiorly and adapted to be screwed upon the sleeve at the upper edge of the bowl A. The exterior diameter of the combustion-chamber of the cylinder B is smaller than the upper interior diameter of the pipe-bowl, thus leaving an annular space, 80 85 *h*, as shown, Figs. 2, 3, 7, and 9.

C is the tobacco-receptacle, also of cylindrical form, provided with a foot or projecting base, *c*. The exterior diameter of this receptacle is slightly less than the interior 90 smaller diameter of the bowl A, so as to form the annular space *b⁴*, as shown, forming a downward or diving draft-passage for the products of combustion.

The height of the tobacco-receptacle is such 95 that when in position in the bowl A there will be a narrow annular aperture or space, *l*, between the upper face of said receptacle and the lower face of the combustion-cylinder B, as shown, Figs. 2, 3, and 9.

D is a follower, composed of a cylindrical casing open at bottom and closed at top, con-

taining a coiled spring, one end of which is attached to the top d of the casing D, and the other free end of said spring bears against the bottom of the tobacco-receptacle C, as shown, 5 Figs. 2 and 3.

The end of the spring E is preferably made to project through the top of the casing D, and has its end formed into a loop, c' , which may serve as a handle to lift the follower and 10 spring out of the tobacco-receptacle and pipe-bowl for the purpose of removing any tobacco, dust, or ashes that may accidentally enter below the follower.

To prevent as much as possible any tobacco or ashes passing below the follower D, 15 I form the casing as shown, Figs. 2 and 3— that is to say, with its upper and lower edges fitting snugly against the interior walls of the tobacco-receptacle C, and reducing its diameter at a point, d' , immediately below the upper closed end of said casing to form an annular chamber, so that any tobacco or ashes that may accidentally pass between the closed top 20 d and the walls of tobacco-receptacle will be arrested by the lower expanded part of the casing D, that, like its top, is made to fit sufficiently tight against the interior wall of the receptacle C without thereby impeding its movements therein.

30 Instead of making the receptacle C a separate part of the pipe-bowl, this and said bowl may be formed of one piece, as shown, Figs. 9, 10, 11, and 12.

It will be seen that the arrangement of 35 parts is not necessarily confined to the particular form of pipe-bowl shown in the drawings, and that they may be applied to other forms, such, for instance, as those usually employed in conjunction with nicotine-reservoirs, and 40 also that the interior configuration of the bowl need not necessarily be cylindrical, nor is it absolutely necessary that the sleeves a^2 b^3 should be provided with screw-threads, as these may be arranged to fit sufficiently tight 45 without such threads to hold them in proper position relatively to each other.

The operation of the devices may be briefly stated as follows: The tobacco-receptacle C being charged with tobacco, either through 50 the flaring or hopper mouth of the cylinder B or by removing said cylinder, the spring E, together with its casing, is depressed, the spring tending to press the casing D and the charge of tobacco above it upward to fill the 55 combustion-chamber b^2 of the cylinder B. The latter chamber being contracted at g , the annular shoulder formed by such contraction will arrest the upward movement of the tobacco under the action of the spring. The parts 60 being now in the position shown by Fig. 3, the tobacco is ignited in the usual manner, and the products of combustion, instead of passing, as usual, through the entire charge, will pass only through that portion within the 65 combustion-chamber, escaping through the narrow annular aperture l between the latter

and the top of the tobacco-receptacle C, and thence into the enlarged annular draft-chamber h , from which these products pass downward through the contracted annular passage b^4 , and thence out through the neck A' into the stem.

By providing the tobacco-receptacle C with a foot, c , I form at the base of the bowl a nicotine-chamber, i , from which the nicotine and 75 saliva may be readily removed.

As the tobacco is consumed fresh tobacco is fed to the chamber b^2 by the follower D under the action of its spring E.

The advantage of this construction and arrangement of pipe-bowl will be readily understood from what has been said above.

Having now described my invention, what I desire to claim, and secure by Letters Patent, is—

1. The combination, with the pipe-bowl and a tobacco-receptacle arranged to form an annular passage between it and the pipe-bowl, of a removable combustion-chamber, having the contracted combustion-zone g , and devices 90 to feed the tobacco thereto, arranged and operating as and for the purpose specified.

2. The combination, with the pipe-bowl, the tobacco-receptacle, and tobacco-feeding devices, of the removable combustion-chamber 95 B, having the contracted part g , and arranged relatively to the tobacco-receptacle to form the annular passage l between it and said receptacle, all arranged and operating as and for the purpose specified.

3. The combination, with the pipe-bowl, of a removable combustion-chamber, a removable tobacco-receptacle, and feeding devices to feed the tobacco to said combustion-chamber, all arranged and operating as and for the purpose specified.

4. The combination, with the pipe-bowl, of the removable combustion-chamber, the removable tobacco-receptacle, and removable feeding devices to feed the tobacco to the 110 combustion-chamber, all arranged and operating substantially as described, and for the purpose specified.

5. The combination, with the bowl A, of the removable receptacle C, provided with a foot, 115 c , as and for the purpose specified.

6. The combination, with the receptacle C and follower-casing D, of the spring E, projecting through the top d and having loop c' , substantially as and for the purpose specified.

7. The combination, with the bowl A, the cylinder B, having a flaring mouth, b' , a combustion-chamber, b^2 , and a contracted part, g , between the two, of the receptacle C, the follower D, and spring E, all arranged and operating substantially as and for the purpose specified.

GUSTAV RÖMISCH.
